FRINGE HEADING.

No. 15,395.

Patented Sept. 9, 1884.

UNITED STATES PATENT OFFICE.

CHARLES WEINBERG, OF NEW YORK, N. Y.

DESIGN FOR FRINGE-HEADING.

SPECIFICATION forming part of Design No. 15,395, dated September 9, 1884.

Application filed July 8, 1884. Term of patent 7 years.

To all whom it may concern:

Be it known that I, CHARLES WEINBERG, of the city and State of New York, have invented and produced a new Design for Heading for Upholstery-Fringe, of which the following is a specification.

This design is shown in the accompanying photograph; and it relates to the ornamental character of the woven heading for upholstery-fringe. At the top of the heading there are lines of stripes at a b c, with cross-threads, forming what is known as a "gimp pattern," and at the bottom part of the heading there is a stripe, d, composed of narrow transverse stripes. The 15 intermediate portion to which my ornamental design especially relates consists of cords e e upon a surface or background of transverse cords. The general direction of these cords e is lengthwise of the heading; but they are in 20 waving or curved lines, converging and diverging, so as to produce an appearance similar to the links of chains. The spaces between the cords through which the transverse cords appear are elliptical at i and diamond-shaped 25 at o.

I have represented a heading with the longitudinal cords similar to three lines of chains. They may be increased or decreased in number. These cords in imitation of longitudinal chains, with the gimp wave at the top of 30 the heading, form a handsome contrast and a heading that is well adapted to upholstery-fringe.

I have shown at k tassels for such fringe. The aforesaid design for a fringe-heading, however, is not limited to any particular kind of 35 tassels.

I claim as my invention—

The design for the ornamental heading for fringe, having lines of cords upon its surface 40 in imitation of chains and a gimp edge to the heading, substantially as described and represented.

Signed by me this 27th day of June, A. D. 1884.

CHARLES WEINBERG.
